William H. Low,
Attorney.

UNITED STATES PATENT OFFICE.

ALBERT S. ROBINSON, OF ALBANY, NEW YORK.

BALING-PRESS.

SPECIFICATION forming part of Letters Patent No. 244,822, dated July 26, 1881.

Application filed November 22, 1880. (No model.)

To all whom it may concern:

Be it known that I, ALBERT S. ROBINSON, of the city and county of Albany, and State of New York, have invented certain new and useful Improvements in Baling-Presses, of which the following is a specification.

My invention relates to improvements in the class of baling-presses in which the material to be compressed is fed into one end of the press-box and the finished bale is ejected from the opposite end; and the objects of my improvements are, first, to provide the press with a powerful compressing mechanism that is adapted to operate by means of power continuously acting in one direction; second, to adapt the press to the production of bales of different sizes; and, third, to prevent the material that is forced into the pressing-chamber by the plunger of the machine from being retracted therefrom by the return movement of the plunger. These objects I attain by the mechanism illustrated in the accompanying drawings, which form a part of this specification, and in which—

Figure 1 is a side elevation of my press, with portions of the side broken away for the purpose of showing the underlying parts; Fig. 2, a plan view; Fig. 3, a detached sectional view of the end of the press, showing the gear-wheels not shown in Fig. 1; Fig. 4, an enlarged transverse section, at the line $x-x$, of the press-box when expanded; Fig. 5, an enlarged and detached end view of one of my retaining-rollers; and Figs. 6 and 7 are skeleton-diagrams of the gear-wheels for operating the double toggle-joints.

As represented in the drawings, a is the press-box, made in a rectangular form, having a pressing-chamber, A' , in which the material is compressed directly behind it, and a rearward extension, forming the baling-chamber A^2 , (corresponding in size and shape to the transverse section of the pressing-chamber A' ,) provided with a close top and bottom, but whose sides are simply provided with the top and bottom guiding-strips a , whereby the bales are guided through the chamber, and the opening A^4 is formed to facilitate the operation of tying off the compressed bale while in the baling-chamber. A forward extension, A^3 , is attached to the press-box A for forming a

framing for receiving the mechanism for actuating the compressing mechanism.

B is a plunger fitted to slide freely in the press-box A , and having fixed thereto a rod, b , that is guided by the cross-piece a' . A cross-head, b' , is secured to the outer end of the rod b for receiving the inner ends of the plunger-moving mechanism. Said mechanism consists of duplex toggle-joints—an upper one, C , and lower one, D —so arranged that when the parts are extended to force the plunger to the extremity of its stroke into the pressing-chamber the knuckles c and d will lie at their nearest approach to a central line, from which line the said knuckles move outward in opposite directions until they attain the positions shown in Figs. 1 and 3, when the plunger is drawn backward to the other extremity of its stroke. The inner ends of the toggle-joints are pivoted by the pins c' and d' , to the cross-head b' , and their outer ends are pivoted in a like manner to the cross-piece a' by the pins c^2 and d^2 .

Motion is imparted to the toggle-joints by means of the geared crank-wheels E and F , whose centers of rotation are independent of each other, but ranged in the same continuous line, so that the disks of the wheels will face each other from the opposite side of the press, the wheel E being connected by the pitman e to the upper toggle-joint, C , and the wheel F by the pitman f to the lower toggle-joint, D . The wheels E and F are uniform in size, and are arranged to rotate isochronously, but in opposite directions, as indicated by the diagrams, Figs. 6 and 7, this uniformity of speed but opposition in movement being necessary to produce the motions of the duplex toggle-joints in opposite directions. Motion is imparted to the wheels E and F by a driving-shaft, G , through trains of gearing, (indicated by the skeleton-diagrams in Figs. 6 and 7.) In Fig. 6 the wheel E is shown as rotating in the same direction as the driving-shaft, and to effect this the said shaft has secured to it a pinion, g , that gears into a wheel, H , secured to the shaft h' , which is also provided with a pinion, h , that gears into the wheel E . In Fig. 7 the wheel F is shown as rotating in an opposite direction to the driving-shaft. This is effected by means of a pinion, i , secured to the shaft G and gearing into a pinion, i' , of the

same size, that gears into the wheel J, secured to the shaft j' , which also carries the pinion j , that gears into the wheel F. The gear-wheels H and J and pinions g , i , and i' are contained 5 between the plates attached to the framing of the forward extension, A³, and the positions of said wheels are indicated by the dotted lines in Figs. 1 and 3.

K is a hopper fixed on the top of the machine, through which the material is fed into the press-box A. At the rear end of the opening for said hopper there is placed a roller, L, provided with longitudinal grooves of angular form, whose deepest incisions are formed by 15 radial lines. Secured to one end of said roller there is a ratchet-wheel, l, into which a pawl, l', engages to prevent the roller from turning backward. Said roller rotates in bearings adapted to move vertically against the resistance of springs l². A second roller, L', of like construction, and provided with the same appliances that are attached to the roller L, is placed in the bottom of the press-box directly opposite the roller L. Both rollers are arranged 25 so that the beveled side of the grooves lying toward the inside of the press-box will be faced toward the inner end of the plunger B. By this arrangement the rollers are adapted to yield outwardly and to rotate on their bearings when an excessive quantity of material 30 is carried forward by the plunger. A guard, M, is placed over the roller L, inside of the hopper K, to prevent the material, as it is fed into the press-box, from clogging said roller. 35 The sides of the press-box A and baling-chamber A⁴ are adapted to be adjusted sideways, for the purpose of making bales of different widths. To effect this purpose there are attached to the top and bottom of the press 40 the bosses N, having a hole at each end tapped to receive the screws O, that have bearings, in which they rotate, fixed to the longitudinal frame-timbers of the press. Said screws are provided at their outer ends with miter-wheels 45 P, which engage with like wheels P', secured to the vertical shafts Q at the sides of the press. On the upper end of each of said shafts there is a head, q, for receiving a crank or other suitable appliance, by which the shaft 50 may be rotated to turn the screws connected thereto, so as to move the sides of the press

out or in, as occasion may require, and the top and bottom girts, R, are provided with slotted openings for the tie-bolts r, so as to allow for the adjustment above described. When the 55 press-box and baling-chamber are widened, as described, filling-in pieces T are inserted in the top and bottom of the press, and cheek-pieces b² are secured to the sides of the plunger B, so that these several parts will conform in 60 size to each other.

I claim as my invention—

1. In a baling-press, the combination, with the duplex toggle-joints C and D, of the crank-wheels E and F, secured to separate and independent shafts, whose centers are ranged in a continuous line that is common to both, said wheels being arranged to rotate synchronously in opposite directions and connected to said toggle-joints in the manner described, so that 65 each revolution of said wheels will produce a complete movement of the toggle-joints to move the plunger B through both phases of its reciprocating movement, as herein specified.

2. In a baling-press, the baling-chamber A², 75 provided at two of its oppositely-located vertical sides with a single opening, A⁴, and guiding-strips a, for the purpose of facilitating the operation of tying off the bale before it is ejected from the press, as herein specified. 80

3. In a baling-press, the combination, with the pressing-chamber A', of the baling-chamber A², arranged in relation to the pressing-chamber as herein described, and provided at each of its vertical sides with a single opening, A⁴, and top and bottom guiding-strips, a, 85 as and for the purpose herein specified.

4. The rollers L, provided with angular longitudinal grooves, as herein described, and having the ratchet l and pawl l', the said roller 90 being adapted to rotate in yielding bearings, and arranged in relation to the hopper k, as herein specified.

5. A baling-press provided with adjustable pressing and baling chamber and an adjustable plunger, whereby the press is adapted to produce bales of different widths, as herein specified. 95
